ROCK BIT

Alfred C. Catland, Alhambra, Calif., assignor to
 Globe Oil Tools Company, Los Nietos, Calif., a
 corporation of California

Application November 5, 1937, Serial No. 172,967

7 Claims. (Cl. 308—198)

This invention relates to well drilling tools and relates more particularly to a rock bit for use in the rotary method of well drilling. A general object of this invention is to provide a rock bit embodying improved and particularly effective anti-friction bearing means for the roller cutters.

Another object of this invention is to provide a rock bit embodying anti-friction ball bearings for the cutters in which the balls assume the end 10 thrusts in both axial directions, as well as the radial thrusts.

Another object of this invention is to provide a rock bit of the character mentioned in which the bearings for the cutters are simple and inexpensive to manufacture and are easily and quickly assembled.

Another object of this invention is to provide a rock bit of the character mentioned in which the balls are inserted in the ball grooves through 20 notches in the race, the notches later being closed by blocks formed and located so that the race and blocks are not cracked or broken away by the balls during operation of the bit.

Another object of this invention is to provide a 25 dependable, inexpensive and practical means for removably attaching a cutter supporting pin or bolt to the body of a well bit.

The various objects and features of my invention will be fully understood from the following 30 detailed description of a typical preferred form and application of the invention, throughout which description reference is made to the accompanying drawing, in which:

Fig. 1 is a side elevation of the well bit construction provided by this invention with the lower portion broken away to illustrate the outer cutters and the bearing means in vertical cross section. Fig. 2 is an enlarged side elevation of the bearing member or race of one of the cutter 35 mounting means. Figs. 3 and 4 are transverse detailed sectional views taken as indicated by lines 3—3 and 4—4, respectively, of Fig. 2. Fig. 5 is an enlarged vertical sectional view of one of the blocks for occupying a ball admitting opening in the race and Fig. 6 is an enlarged side elevation of a split threaded thimble for one of the cutter supporting pins.

The improved rock bit provided by this invention includes, generally, a body 10, outer cutters 11 and bearing means 12 for mounting the outer cutters 11 on the body 10.

The bit body 10 is intended to be connected with the lower end of a rotary well drilling string. A threaded pin 16 may be provided on the upper 55 end of the body 10 to facilitate its connection

with the string. Depending parts are provided on the lower end of the body 10 to carry the bearing means 12 for the cutters 11. A substantially central web 17 projects downwardly from the lower end of the body 10. The web 17 is broadened adjacent its lower end to have two downwardly and outwardly extending wings 18. Two diametrically opposite legs 19 project downwardly from the lower end of the body 10. The legs 19 project outwardly as well as downwardly and the 10 inner sides of the legs 19 oppose the outer sides of the wings 18. In the preferred construction the opposing surfaces or sides of the wings 18 and the legs 19 are flat and parallel and are inclined downwardly and outwardly relative to the central 15 longitudinal axis of the bit. The web 17 and the legs 19 may be integral with the body 10. It is to be understood that the bit body 10 may be provided with the usual circulation ports for handling the circulation fluid used in the rotary 20 method of well drilling. The bit shown includes cross cutters or inner cutters 13 and 14 arranged at opposite sides of the web 17.

The cutters 11 are toothed roller cutters for acting on the outer portion of the bottom wall of 25 the well. There are two outer cutters 11 embodied in the bit, one cutter 11 being supported between each set of opposing wings 18 and legs 19. The cutters 11 are frusto-conical having pitched toothed peripheries and having flat parallel opposite ends. Each cutter 11 has a central longitudinal opening 21 of substantial diameter. Annular ball races or grooves are provided in the walls of the cutter openings 21. In the form of the invention illustrated there are two grooves 22 35 and 23 provided in the wall of each opening 21. The grooves 22 are slightly larger in diameter than the grooves 23. It is to be noted that the ball grooves 22 and 23 are of substantial depth.

The bearing means 12 are in the nature of 40 anti-friction ball bearings for rotatably supporting the cutters 11. As the two bearing means 12 may be identical I will proceed with a detailed description of one of them, it being understood that such description is equally applicable to the 45 other bearing means.

The bearing means 12 includes a bearing member or race 24. The race 24 is a generally cylindrical spool-like member having a central longitudinal opening 25. The race 24 is proportioned to be received in the opening 21 of a cutter 11 with substantial clearance. The opposite ends of the race 24 are flat and parallel and have central outwardly projecting bosses 26. Peripheral ball grooves 27 and 28 are provided 50

in the race 24 to oppose the grooves 22 and 23, respectively, on the interior of a cutter 11. The groove 27 is somewhat larger in diameter than the groove 28 and the two grooves are of substantial depth. Openings or axially extending notches 29 extend into the member 24 from its opposite ends to join the adjacent grooves 27 and 28. The notches 29 extend through the wall of the race 24 to the opening 25 and extend outwardly through the bosses 26. In the preferred construction the two notches 29 are circumferentially offset, as best illustrated in Fig. 2 of the drawing. The notches 29 have flat parallel side walls.

15 The bearing means 12 further includes series of balls 30 cooperating with the sets of opposing grooves 22 and 27 and 23 and 28. The opposing grooves 22 and 27 and 23 and 28 are of such depth that the balls 30 have extensive cooperation with their walls to assume the end thrusts in both directions, as well as the radial thrusts transmitted between the cutter 11 and the race 24. The notches 29 are proportioned to admit the balls 30 to the pairs or sets of opposing grooves and in assembling the balls 30 they are individually passed through the notches 29 into the registering grooves 22 and 27 and 23 and 28, as will be subsequently described.

Blocks 31 are provided to occupy the notches 29 in the bearing member or race 24. The blocks 31 are shaped and proportioned to fit and fully occupy the notches 29. The outer sides of the blocks 31 have curved concave faces 32 forming continuations of the grooves 27 and 28. When the blocks 31 are in place in their notches 29 their outer ends are flush with the flat outer ends of the race 24. The blocks 31 are provided with outwardly projecting extensions 33 which occupy the portions of the notches 29 extending through the bosses 26. The inner sides of the blocks 31 are concave to be flush with and form continuations of the wall of the opening 25. When the blocks 31 are in place in the notches 29 the grooves 27 and 28 are completed by the surfaces 32 of the blocks so that the balls 30 are positively prevented from loss or displacement from the grooves. The balls 30 in turn cooperate with the registering or opposing grooves 22 and 27 and 23 and 28 to prevent relative endwise movement between the race 24 and the cutter 11.

Means is provided to prevent outward displacement of the blocks 31 from the notches 29. An annular groove 35 is provided on the wall of the opening 25 midway between the ends of the race 24. The groove 35 has a deepened middle portion. The groove 35 is partially intersected by or is joined by the notches 29. The blocks 31 are provided with lugs or tongues 36 which project into the deepened portion of the groove 35. A snap ring 37 is sprung into the groove 35 to cooperate with the tongues 36 and thereby limit or prevent outward displacement of the blocks 31 from the notches 29. The tongues 36 and the adjacent portions of the blocks 31 are shaped to be properly engaged by the periphery of the ring 37. The ring 37 is a split resilient annular member that may be compressed and entered in the opening 25 to automatically spring into the groove 35 to cooperate with the 70 tongues 36.

It is believed that it will be apparent how the bearing means 12 may be assembled in a cutter 11. The race 24 is first arranged in the cutter opening 21. The balls 30 are then passed through one of the notches 29 to occupy one

set of opposing grooves 22 and 27 or 23 and 28. When this set of grooves is fully occupied by the balls 30 a block 31 is inserted in the notch 29 to retain the balls in the grooves. The balls 30 are then arranged in the other set or pair of registering grooves 22 and 27 or 23 and 28 in the same manner. The other block 31 is then arranged in its notch 29. The ring 37 is sprung into the groove 35 to cooperate with the tongues 36 for the purpose of retaining the blocks 31 in place. A washer 38 is arranged between the inner end of the race 24 and the outer face of the adjacent wing 18. The washer 38 fits in the opening 21 of the cutter 11 with suitable clearance and surrounds the boss 26 on the inner end of the race 24. The balls 30 in the grooves 23 and 28 cooperate with the washer 38 for the transmission of end thrusts from the cutter 11 to the wing 18. The washer 38 is provided with a lug 39 which projects inwardly at the lower end of the wing 18. A washer 40 is arranged between the outer end of the race 24 and the inner side of the adjacent leg 19. The washer 40 surrounds the boss 26 on the outer end of the race 24 and extends into the cutter opening 21 with suitable clearance. The row of balls 30 in the grooves 22 and 27 cooperates with the washer 40 for the transmission of outward end thrusts from the cutter 11 to the leg 19. A lug 41 is provided on the washer 40 and projects outwardly at the lower end of the leg 19.

When a cutter 11 and its bearing means have been assembled, as described above, the assembly, together with the washers 38 and 40 is arranged between a wing 18 and a leg 19 and the assembly is secured to the body 10. Each wing 18 has a downwardly and inwardly inclined opening 42 and each leg 19 has a correspondingly inclined opening 43 aligned with the opening 42 of the adjacent wing 18. The outer portions of the openings 43 are enlarged and shaped to constitute frusto-conical sockets 44. The means for supporting a bearing means 12 and its cutter 11 consists of a bolt or pin 45 passed inwardly through an opening 42 to extend through the opening 25 in the race member 24 of the bearing means. A frusto-conical spool or nut 46 is arranged in the socket 44 in the adjacent leg 19 and the outer portion of the pin 45 is threaded into the nut. The nut 46 is longitudinally split, as illustrated in Fig. 6, to render it flexible and resilient. The outer end 46a of the nut 46 is pitched to be flush with the outer side of the leg when the nut is in place. A head 48 is provided on the inner end of the pin 45 to engage against the inner side of the wing 18. When the pin 45 is tightened the taper of the nut 46 and the wall of the socket 44 causes the nut to contract tightly onto the pin 45. This prevents loss or displacement of the nut 46. The tightening or wedging of the nut 46 onto the tapered socket 44 also compensates for any inaccuracies there may be in the nut and the wall of the socket. Following the tightening down of the pin 45 the lug 39 is welded to the lower end of the wing 18 and the lug 41 is welded to the lower end of the leg 19 so that the washers 38 and 40 are fixed to the bit body.

In assembling the bearing means 12 and the cutter 11 on the body 10 it is preferred to arrange the race 24 where the notches 29 and the blocks 31 are at the upper side of the race so that the blocks are subjected to a minimum of wear. To assure the proper location of the race 24 and to prevent the race from moving from 75

the proper place a dowel 47 may be assembled in aligned openings in the outer end of the race and the washer 40. As the washer 40 is welded to the leg 19 the dowel 47 serves to prevent turning of the race 24.

It is believed that the utility and practicability of the improved well bit provided by this invention will be readily understood from the foregoing detailed description. In operation the bit 10 is secured to the lower end of the drilling string which is rotated and fed downwardly in the well in the usual manner. The cutters 11 follow an annular path to cut away the formation at the outer portion of the well bore. The cutters 11 15 are supported by the pairs of series of balls 30 to freely rotate about inclined axes. The balls 30 are operable to transmit end thrusts in both axial directions as well as the radial thrusts so that the cutters do not bear against the body 20 surfaces or the thrust washers. The races 24 are long wearing because the notches 29 are at their upper sides where the blocks 31 and the parts adjacent the notches 29 are subjected to a minimum of pressure and wear. The bearing 25 means 12 of the cutters 11 are easy to manufacture and are simple to assemble.

Having described only a typical preferred form and application of my invention, I do not wish to be limited or restricted to the specific details 30 herein set forth, but wish to reserve to myself any variations or modifications that may appear to those skilled in the art or fall within the scope of the following claims.

Having described my invention, I claim:

1. In combination, a rotary element having an opening and a ball groove in the wall of the opening, a tubular race in the opening having an internal annular recess and an external ball groove between its ends opposing the first named groove 40 and having a notch extending inwardly from one end and joining the second mentioned groove, balls inserted through the notch to cooperate with the grooves, a block filling the notch, and means for retaining the block in the notch 45 comprising a tongue on the block extending into the recess, and a spring ring in the recess cooperating with the tongue.

2. In combination, a rotary element having an opening and spaced ball grooves in the wall of 50 the opening, a tubular race in the opening having spaced races opposing the races in the element, and having a notch extending from one end to one of the last named grooves and a notch extending from the other end to the other 55 of the said last named grooves, balls introduced through the notches to the pairs of opposing grooves, blocks inserted in the notches to complete the said last named grooves, and a single spring ring in the race retaining the blocks in the notches.

3. In combination, a rotary element having an opening and spaced ball grooves in the wall of the opening, a tubular race in the opening having spaced races opposing the races in the element, and having a notch extending from one end to one of the last named grooves and a notch extending from the other end to the other of the said last named grooves, balls introduced through the notches to the pairs of opposing 60 grooves, blocks inserted in the notches to com-

plete the said last named grooves, and means on the race retaining the blocks in the notches, said means including tongues on the inner ends of the blocks, and a ring in the race cooperating with the tongues.

4. In combination, a roller having an opening and spaced ball grooves in the wall of the opening, a tubular race in the opening having spaced races opposing the races in the roller, and having a notch extending from one end to one of the last named grooves and a notch extending from the other end to the other of the said last named grooves, balls introduced through the notches to the pairs of opposing grooves, blocks inserted in the notches to complete the said last named 10 grooves, and means on the race retaining the blocks in the notches, there being a groove in the interior of the race, said means including tongues on the blocks extending into the groove in the interior of the race, and a spring ring in 15 the said groove cooperating with the tongues.

5. In combination, a roller having an opening and a ball groove in the wall of the opening, a tubular race in the opening having a ball groove 20 opposing the first named groove and having a notch extending inwardly from one end and joining the second mentioned groove, balls inserted through the notch to cooperate with the grooves, a block filling the notch, and means carried by the race retaining the block in the notch, said 25 means including a tongue on the block recessed in the interior of the race and a spring ring in the race cooperating with the tongue.

6. In combination, spaced supporting parts, a roller arranged between said parts and having an opening with a ball groove in its wall, a support extending between said parts and passing through said opening, a race on the support having an external groove opposing the first mentioned groove, a boss on an end of the race, the race having a notch extending from said end through the boss to the said external groove, balls inserted through the notch to the grooves to rotatably support the roller, a block occupying the notch, an extension on the block occupying 45 the portion of the notch in the boss, and a washer on the boss between said end of the race and one of said parts cooperating with the extension and a side of the block.

7. In combination, spaced supporting parts, a 50 rotary element arranged between said parts and having an opening with a ball groove in its wall, a support extending between said parts and passing through said opening, a race on the support having an external groove opposing the first 55 mentioned groove, a boss on an end of the race, the race having a notch extending from said end through the boss to the said external groove, balls inserted through the notch to the grooves to rotatably support the element, a block occupying the notch, an extension on the block occupying the portion of the notch in the boss, the notch and block being at the upper side of the race, a washer on the boss between said end of the race and one of said parts cooperating with the 60 extension and a side of the block, means holding the washer against rotation, and means securing the race to the washer to prevent rotation of the race.
